(57) CLAIM

The ornamental design for the bowl-shaped container, as shown and described.

DESCRIPTION

FIG. 1 is a side view of a bowl-shaped container, side views taken from the opposite side and taken perpendicular to the view shown in FIG. 1 are the same as the view shown in FIG. 1;

FIG. 2 is a perspective view of the bowl-shaped container shown in FIG. 1;

FIG. 3 is a top view of the bowl-shaped container shown in FIG. 1;

FIG. 4 is a bottom view of the bowl-shaped container shown in FIG. 1; and,

FIG. 5 is an enlarged view of a portion of the bowl-shaped container shown in FIG. 1.

The dashed lines are shown in the views for illustrative purposes only and form no part of the claimed design.
